UNITED STATES PATENT OFFICE.

HERBERT FREDERICK FREULER, OF WALLA WALLA, WASHINGTON.

PROCESS FOR MANUFACTURING GASES.

1,286,577.

Specification of Letters Patent.

Patented Dec. 3, 1918.

Application filed June 6, 1916. Serial No. 101,945.

To all whom it may concern:

Be it known that I, HERBERT F. FREULER, a citizen of the United States, and a resident of Walla Walla, in the county of Walla 5 Walla and State of Washington, have invented an Improvement in Processes for Manufacturing Gases, of which the following is a specification.

This invention is an improvement in the 10 manufacture of gases and has particular reference to the production of carbon mon-oxid and hydrogen.

An object of the invention is to provide a process for making gases wherein a mass 15 of carbon substance is electrically charged by an initial current of comparatively high voltage whereby the carbon is heated after which the voltage may be reduced and steam passed through the mass whereupon the 20 oxygen of the steam combines with the carbon and leaves the hydrogen free thus forming the desired gases.

The inventive idea involved is capable of receiving a variety of mechanical expres- 25 sions, one of which, for the purpose of illustrating the invention, is shown in the accompanying drawings, in which—

Figure 1 is a vertical sectional view of the furnace constructed in accordance with 30 the invention.

Fig. 2 is an enlarged sectional view of the mounting for one of the electrodes used in connection with the invention.

Fig. 3 is a fragmentary side elevation of 35 the furnace.

Fig. 4 is a similar view taken at right angles to Fig. 3.

The invention, as illustrated in the drawings, is now believed to be in its preferred 40 form and consists of a furnace having a metallic casing 5 hermetically sealed at the seams and at the entrance openings 6 and 7 formed in the top and sides of the furnace, respectively, to permit of access to the in- 45 terior thereof. The casing 5 is provided with a lining 8 formed of an electrical insulating refractory material, preferably fire brick. The furnace is adapted to contain a mass of carbon or charcoal 9 which is 50 heated through the medium of a series of carbon electrodes 10 mounted in opposite sides of the furnace and projecting laterally into said mass.

Each of the electrodes 10 is mounted in a 55 stuffing box or gland 11 separated from the

casing 5 by means of insulation 12 and said electrode is adjustable laterally in said fire box whereby the distance between the inner ends of the several electrodes in the furnace may be varied. The electrodes 10 are connected to a suitable source of electric current of comparatively high voltage, depending upon the size of the furnace, which current is adapted to be passed through the mass of carbon material 9 in order that the same 60 may be heated. The electrodes are initially adjusted so that the inner end of each is in close proximity with the one opposite, the same being so adjusted owing to the resistance of charcoal or other carbon material at 70 a low temperature. As the temperature rises and the conductivity of the carbon mass increases, which could be indicated by a meter (not shown) connected to the source of current, the electrodes are withdrawn 75 outwardly but not sufficient to destroy the contact between the same and said mass. After this operation, the initial current may be disconnected and a current of lower voltage may be substituted, which change af- 80 fords improved means for regulating the heat, as with the low resistance of the heated carbon too much current might pass through the mass at the initial voltage and thus cause a higher temperature than is required, 85 which would result in a loss of electrical power.

After the carbon mass has been heated to the desired and proper temperature, steam, preferably superheated, furnished from a 90 source not shown, is injected into the mass by means of a spraying device 13 having an inlet 14 extending up through the bottom of the furnace to supply the steam to the several nozzle openings 15 which are 95 adapted to distribute the fluid in all directions. Upon the passage through the carbon mass of the superheated steam the latter is decomposed and the oxygen thereof combines with the charcoal or carbon to form 100 carbon monoxid while the hydrogen is left free. The gases thus formed are permitted to escape from the furnace through the outlets 16 in the top thereof communicating with the pipes 17 which convey the gases to 105 a source.

What is claimed is:

1. The herein described process for the production of gases consisting of first electrically heating a mass of carbon material 110

with a current of comparatively high voltage, reducing said voltage to regulate the temperature of said mass, and then injecting super-heated steam into the mass whereby the fluid is decomposed and the oxygen of the steam combines with the carbon forming carbon monoxid and free hydrogen.

2. The herein described process for the 10 production of gases, which consists in first subjecting a mass of carbon material to a current of comparatively high voltage, reducing the voltage when the mass has been heated and its resistance lowered, and subsequently injecting superheated steam into the mass, whereby the steam is decomposed

and carbon monoxid and free hydrogen are formed.

3. The herein described process for the production of gases, which consists in first 20 subjecting a mass of carbon material disposed between two conducting electrodes, to a current of comparatively high voltage, separating the electrodes farther apart when the mass has been heated and its resistance lowered, reducing the voltage supplied to the electrodes, and subsequently injecting superheated steam into the mass, whereby the steam is decomposed and carbon monoxid and free hydrogen are formed. 25

HERBERT FREDERICK FREULER.
